REFRIGERATOR DEFROSTING DEVICE

Claude W. Greever, Jr., Welch, W. Va.

Application September 9, 1931, Serial No. 561,907

2 Claims. (CL 62—4)

This invention relates to a device for defrosting mechanical refrigerators, and has for its primary object to provide, in a manner as herein-after set forth, a device of this character embodying a novel construction, combination, and arrangement of parts whereby the electric motor of the mechanical refrigerator will be shut off periodically for a length of time sufficient to permit the temperature to rise in the refrigerator and defrost the cooling unit.

Other objects of the invention are to provide a refrigerator defrosting device of the aforementioned character which will be simple in construction, strong, durable efficient and reliable in operation and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in front elevation of a refrigerator equipped with a defrosting device in accordance with the present invention.

Figure 2 is a view in elevation of the device with the closure plate of the casing removed.

Figure 3 is a view of a modified form of the invention.

Referring now to the drawings in detail, it will be seen that the reference numeral 1 designates a conventional mechanical refrigerator having therein a cooling unit 2. The reference numeral 3 designates a casing mounted on top of the refrigerator 1 and journaled for rotation in the casing is a horizontal shaft 4 having fixed thereon a large gear 5.

The reference numeral 6 designates a clock 40 which may be of conventional type which is disposed on the refrigerator 1 adjacent the casing 3. The shaft 7 is journaled in the casing 3 and extends outwardly therefrom and is operatively connected to the clock 6 for actuation thereby.

A comparatively small gear 8 is fixed on the shaft 7 within the casing 3 and is constantly in mesh with the large gear 5 for driving same.

The reference numeral 9 designates generally a switch which is interposed in the electric circuit 10 to the electric motor (not shown) of the refrigerator 1. The switch 9 comprises a stationary contact 11 and a movable contact 12 mounted on an intermediate portion of a flexible arm 13. A cam 14 is fixed on the shaft 4 and 55 is adapted for engagement with the free end

portion of the arm 13 in a manner to disengage the contacts 11 and 12 with each complete revolution of the shaft 4.

A bracket 15 is mounted in the casing 3 and is provided with an opening in which is operable the free end portion of a keeper 16 which is pivotally mounted on the arm 13. The keeper 16 is provided with a hook or lug 17 which is engageable with the bracket 15 for releasably securing the arm 13 in raised position for maintaining the switch 9 open after the cam 14 passes the arm 13.

A spring 18 is connected with the free end portion of the keeper 16 for yieldingly urging said keeper into operative engagement with the bracket 15.

Also mounted in the casing 3 is a bellows thermostat 19 having depending therefrom into the refrigerator 1 adjacent the cooling unit 2 a thermal tube 20 having an enlargement 21 on its lower end. The reference numeral 23 designates generally an electric switch which is mounted in the casing 3 adjacent the bellows thermostat 19. The switch 23 comprises the stationary contact 24 and a movable contact 25 mounted on an intermediate portion of a flexible arm 26 which is operatively engaged with the upper end of the bellows thermostat 19 for actuation thereby.

A coil spring 27 is operatively engaged with the arm 26 for yieldingly urging said arm in a direction to open the switch 23. The tension of the coil spring 27 may be regulated as desired through the medium of an adjusting screw 28 which is threadedly mounted in the casing 3 and operatively engaged with the coil spring.

The reference numeral 29 designates an electro-magnet which is mounted in the casing 3 in a position to attract the keeper 16 thereto when said magnet is energized, thus swinging the keeper from its operative to its inoperative position against the tension of the spring 18 and permitting the switch 9 to close.

An electric circuit 30 connects the electro-magnet 29 with the motor circuit 10 and the switch 23 is interposed in said circuit 30.

In operation, the switch 9 is normally closed to permit the electric current to pass through the motor of the refrigerator 1. The shaft 4 is driven at the desired speed by the clock 6 to complete one revolution, for example, every ten days. At the completion of each revolution of the shaft 4, the cam 14 engages the arm 13 and opens the switch 9, thereby de-energizing the electric motor of the refrigerator 1.

The cooling unit 2 of the refrigerator is thus

rendered inoperative and the temperature in said refrigerator slowly rises and defrosts the cooling unit. As the temperature in the refrigerator rises, the bellows thermostat 19 is, of course, expanded. As before stated, when the arm 13 is raised by the cam 14 to open the switch 9, the keeper 16 is caused by the spring 18 to engage the bracket 15 to secure said arm 13 in a raised position, thereby maintaining the switch 9 open.

When the bellows thermostat 19 is expanded by the rising temperature in the refrigerator 1 and consequently in the thermal tube 20 the switch 23 is closed thereby energizing the electro-magnet 29. The energized electro-magnet 29 attracts the keeper 16 thereto as hereinbefore explained, thereby disengaging the hook or lug 17 from the bracket 15 and permitting the arm 13 to fall, thereby closing the switch 9.

The electric motor of the refrigerator 1 is thus again energized to function after the defrosting operation.

In the modified form of the invention illustrated in Figure 3 of the drawings, electric switches designated generally by the reference numerals 31 and 32 are interposed in the electric circuit 10 of the electric motor of the refrigerator. The switch 31 comprises a resilient, bifurcated stationary contact 33 and a movable blade contact 34, mounted on a pivoted lever 35 and engageable between the bifurcations of said contact 33 and frictionally retained thereby.

The switch 32 comprises a contact 36 mounted on an intermediate portion of a flexible arm 37 having its free end portion disposed beneath the free end portion of the lever 35 for engagement therewith. The switch 32 further includes a contact 38 engageable with the contact 36 and mounted on an intermediate portion of a flexible arm 39, the free end portion of which is engaged with the upper end of the bellows thermostat 19 for actuation thereby.

In the operation of the modification shown in Figure 3 of the drawings, the switch 31 is normally closed. As the temperature in the refrigerator rises, the bellows thermostat 19 expands and closes the switch 32, thus energizing the motor of the refrigerator cooling unit. After the cooling unit has functioned for a sufficient length of time, the temperature in the refrigerator, of course, drops, thereby causing the bellows thermostat 19 to contract to open the switch 32 and deenergize the motor.

When it is desired to defrost the cooling unit 55 of the refrigerator, the switch 31 is opened by manually actuating the hand lever 35 in a manner to disengage the contact 34 from the contact 33. Thus, the electric circuit to the motor

of the refrigerator cooling unit has been manually opened, and the temperature in the refrigerator begins to rise. As the temperature rises, the bellows thermostat 19 is expanded and the switch 32 is first closed. However, the switch 31 is still open and, therefore, the motor circuit is also still open. After the switch 32 has been closed, the temperature in the refrigerator continues to rise until the bellows thermostat 19 has been expanded sufficiently to close the switch 31 through the medium of the arm 37 of the switch 32 which is engaged beneath the lever 35 of said switch 31. By this time, the cooling unit of the refrigerator will have been in-operative for a sufficient length of time to permit the temperature in the refrigerator to rise sufficiently to defrost said cooling unit. The switch 31 remains closed until it is again manually opened for defrosting the cooling unit of the refrigerator.

It is believed that the many advantages of a refrigerator defrosting device in accordance with the present invention will be readily understood, and although the preferred embodiments of the invention are as illustrated and described, it is to be understood that changes in the details of construction and in the combination and arrangement of parts may be resorted to which will fall within the scope of the invention as claimed.

What is claimed as new is:

1. A defrosting device for mechanical refrigerators of the type having a cooling unit and electric motor actuated means for operating the cooling unit, comprising, in combination, a switch interposed in the motor circuit, and a thermally closed switch interposed in the motor circuit and operatively engageable with the first named switch for closing said first named switch.

2. A defrosting device for mechanical refrigerators of the type having a cooling unit and electric motor actuated means for operating the cooling unit, comprising, in combination, a manually opened switch interposed in the motor circuit, a thermostat operatively connected with the refrigerator, and another switch interposed in the motor circuit and connected with the thermostat for actuation to closed position thereby, the second named switch being operatively engageable with the first named switch and constituting means for operatively connecting said first named switch to the thermostat for actuation to closed position by said thermostat.
